(57) **CLAIM**

The ornamental design for a cap with catheter, as shown and described.

DESCRIPTION

FIG. 1 is a perspective view of a cap with catheter showing my new design;
FIG. 2 is another perspective view of the cap with catheter on top of a bottle;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 of FIG. 2 thereof. The broken lines in the drawings illustrate the environment of the cap with catheter which forms no part of the claimed design.

1 Claim, 9 Drawing Sheets
